UNITED STATES PATENT OFFICE

THOMAS A. LUCY, OF ASHEVILLE, NORTH CAROLINA, ASSIGNOR TO INGALLS STEEL PRODUCTS COMPANY, OF BIRMINGHAM, ALABAMA

SCREED CLIP

Application filed March 24, 1927. Serial No. 177,859.

This invention relates to the art of concrete construction, and more particularly to a device for holding a wooden nailing strip, or screed, in place during the pouring of the concrete, as in concrete floors, such device being commonly known as a screed clip.

One of the objects of this invention is to provide a screed clip which will be strong, simple in construction, economical of manufacture and efficient in its operation.

With screed clips as heretofore manufactured, it has been necessary to provide some independent means for anchoring them in place. A great many concrete floors are at present constructed by using expanded metal lathing as a bottom portion of the form, in which case the screed clips have been anchored by wedges. Another object, therefore, is to provide a screed clip which may be securely anchored to such expanded metal lathing without the use of any independent anchoring means.

Screed clips as constructed at the present time are of sheet metal, the sheet metal portions materially obstructing the flow of the concrete in pouring, requiring careful supervision and additional labor in securely tamping the concrete around the clip.

A further object, therefore, is to provide a screed clip that will not obstruct the flow of the concrete when being poured.

Further objects will appear from the detail description taken in connection with the accompanying drawings, in which—

Figure 1 is a perspective view showing a screed clip embodying this invention;

Figure 2 is a side view showing such a screed in place;

Figure 3 is an end view similar to Figure 2;

Figure 4 is a perspective view showing a clip embodying this invention in use with wooden concrete forms;

Figure 5 is a sectional view of a concrete floor slab showing the use of the clip in connection with a straight-edge; and

Figure 6 is a sectional view of a finished floor.

Referring to the accompanying drawings, 1 designates the upright portions of such a screed clip, 2 designates the base and 3 the

horizontal supporting portion. The screed clip is constructed of one continuous piece of bar metal, preferably of circular cross section. In forming such a screed clip from a straight filar bar, at a distance from one end 55 a little greater than the height of the upright portion, the bar is bent at a right angle at the point 4; at a distance therefrom equal to one-half the length of the base, and at point 5 the bar is bent back upon itself, the two 60 lengths of wire lying side by side in a horizontal plane; at a distance therefrom equal to the length of the base, at point 6, the bar is again bent back upon itself to point 4, where it is again bent at right angles and 65 following the previously formed portion of the upright portion to the height at which the screed is to be held, point 7; there the bar is bent forming the horizontal supporting portion 3, equal in length to the width of 70 the screed, perpendicular to the plane of the previously formed portion and ending at point 8; from thence the bar is bent to form the other upright portion and base in the same manner as previously described with 75 respect to the first, but in reverse order of operation. At points 4 or 8, the joints may be welded together, thus giving greater rigidity to the structure. The ends of the uprights 1 are bent over, as shown at 10. 80

The form of the base is such that the ends thereof may be tucked into the folds of expanded metal lathing, as shown in Figures 2 and 3, it being obvious when thus placed it will be held securely in position. The 85 screed 9 is sprung in between the upright 1 and placed upon the horizontal portion 3. After the screed is in place, the portion 10 may be driven into the screed to securely hold it in position, a slight blow of a hammer 90 serving to imbed such portion 10 in the screed, thus securely fastening the screed in place, eliminating the use of nails or other additional or independent means of fastening. The screed clip is constructed so that 95 the height of the horizontal portion 3, plus the thickness of the screed, will be equal to the thickness of the concrete to be poured. Thus, when the concrete is poured, the top of the screed is level with the top of the concrete. 100

When used with wooden forms, the clip may be applied as shown in Figures 4 to 6 inclusive. The clip may be nailed to the forms 11, as shown in Figure 4, the nails 12 being bent over the base of the clip.

The clips so placed may be used to level the concrete slab. Before the concrete has been poured, a wooden strip or a pipe 13 may be laid on the support 3 (or the screed itself 10 may be used) and a straight-edge 14 may be dragged over the strip or pipe to level the slab. If a space is to be left between the slab and the floor, the straight-edge is notched, as shown in Figure 5. If the floor is to rest 15 directly on the slab, no notch is used. The flooring 15 is nailed directly to the screed in either case.

It will thus be seen that the invention accomplishes its objects. It is economical in 20 construction since it uses stock bar metal and there is no waste in cutting; moreover, the method of manufacture is simple and inexpensive, and resulting in a rigid structure. The form of the base is such that the ends 25 thereof may readily be tucked into the folds of expanded metal lathing forming the bottom of the form, without the use of any independent anchoring means, such as ties or wedges. The scant skeleton form of the clip 30 affords very little resistance to the flow of the concrete in pouring, thereby reducing the amount of labor and supervision necessary in pouring a structure using such a screed clip and insuring perfect envelopment of the 35 screed by the concrete. The clip thereby becomes in reality a reinforcing member adding to rather than detracting from the strength of the completed concrete structure. The bent over portion at the top of the clip 40 holds the screed in place, eliminating the use of separate fasteners.

In the construction of this clip it is to be noted that a filar bar of metal is used, such as a wire or narrow strip as distinguished 45 from a broad sheet or plate. The advantage of this construction is that the filar bars do not obstruct the flow of concrete around them and the difficulty of having vacant spaces in the finished slab due to obstruction of the 50 flow by parts of the clip is overcome. Also the narrow bar makes narrow toes 6 which are easily inserted into the meshes of metal lath and the like.

It is obvious that various changes may be 55 made within the scope of the appended claims in the details of construction without departing from the spirit of this invention; it is to be understood, therefore, that this invention is not limited to the specific details 60 shown and described.

Having thus described the invention, what is claimed is:

1. A screed clip having upright portions, base portions and a horizontal portion constructed of bar metal, said horizontal por-

tion being secured to said upright portions at the points of intersection.

2. A screed clip having upright portions and a horizontal portion all constructed of bar metal, said horizontal portion being fastened to said upright portions by welding 70 at their points of intersection.

3. A screed clip of filar bar metal having upright portions formed with fastening members adapted to be imbedded in the 75 screed.

4. A screed clip of filar bar metal having upright portions, base portions extending outwardly from each of said upright portions and in opposite directions, and a horizontal 80 portion connecting said upright portions.

5. A screed clip having upright portions, base portions extending in opposite directions from each of said upright portions, and a horizontal portion constructed of bar metal, 85 said horizontal portion being secured to said upright portions at the points of intersection.

6. A screed clip of filar bar metal having upright portions formed with inturned ends adapted to be embedded in the screed, thereby 90 to retain said screed against movement.

7. A screed clip of filar bar metal comprising an upright portion, base members extending outwardly therefrom, and adapted for insertion in the mesh of expanded metal lath, and a screed support mounted upon and above said base members, said upright portion having an inturned end adapted to be embedded in the screed. 95

8. A screed clip of filar bar metal having an integral fastening member formed by bending an end of said clip, said member adapted to embrace the screed, and said end adapted to be embedded in the screed. 100

9. A screed clip of filar bar iron having base portions extending forwardly and rearwardly and formed of a portion of the bar bent back upon itself, a transverse support formed of the middle portion of the bar bent upwardly from said base portions, and upright securing elements formed of the ends of the bar extending upwardly from said base portions and turned inwardly to form prongs to be imbedded in the screed. 105

In testimony whereof I affix my signature 110 this 11th day of March, 1927.

THOMAS A. LUCY.

CERTIFICATE OF CORRECTION.

Patent No. 1,779,885.

Granted October 28, 1930, to

THOMAS A. LUCY.

It is hereby certified that error appears in the printed specification of the above numbered patent requiring correction as follows: Page 1, line 52, after "of" second occurrence, insert the word filar; and that the said Letters Patent should be read with this correction therein that the same may conform to the record of the case in the Patent Office.

Signed and sealed this 9th day of December, A. D. 1930.

**M. J. Moore,
Acting Commissioner of Patents.**
